WASHING MACHINE

Oliver J. Chayle, South Bend, Ind., assignor, by
mesne assignments, to American Machine and
Metals, Inc., East Moline, Ill., a corporation of
Delaware

Application February 18, 1939, Serial No. 257,245

4 Claims. (Cl. 68—21)

This invention relates to washing machines and more particularly to washing machines having a single container in which the operations of washing and drying are carried out.

An object of the invention is to provide an improved machine in which the drying operation is carried out by means of fluid pressure exerted on a diaphragm which presses the clothes against a rigid part of the machine.

Another object is to provide an automatic control for such a machine.

Another object is to provide means insuring ease of operation of the machine including means for stopping the motion of the container in a predetermined position so that the clothes doors are always in alignment and so that the drains are always at the lowermost portion of the machine.

Still another object is to provide an arrangement of such a machine in which the driving means is utilized to provide sufficient fluid pressure for operating the extracting means.

The above and other desirable objects and particular arrangements of parts will become apparent upon reading the following detailed description of one preferred embodiment of my invention shown in the accompanying drawings in which:

Figure 1 is a vertical axial section through the washing machine taken in a plane perpendicular to the front face of the machine;

Figure 2 is a section on the line 2—2 of Figure 1;

Figure 3 is a section on the line 3—3 of Figure 1 with parts of the drain pan broken away;

Figure 4 is an axial section through the pump;

Figure 5 is a transverse section through the pump on the line 5—5 of Figure 4;

Figure 6 is a wiring diagram of the machine; and

Figure 7 is a diagram of a preferred washing cycle of the machine.

My novel machine comprises a generally box-like base 10 having a centrally disposed vertically recessed boss 11 in which a vertical shaft 12 is secured by means of a pin 14.

At the upper end of the shaft 12 is a universal joint 16 forming a connection between the shaft 12 and the base casting 18 of a semi-spherical washing container or clothes basket designated 20 generally by the numeral 20.

The container 20 comprises the base casting 18, which is circular, and plane on its upper surface, a semi-spherical perforated sheet metal inner casing member 22 secured to the upper surface of

the base casting by means of a flange 24 and an imperforate outer casing member 26 secured to the base casting 18 in surrounding but spaced relationship with the inner casing 22.

5 The casing members 22 and 26 are each formed with a circular opening concentric with their axis and the two members are preferably secured together by a flange forming part of a door frame 28 surrounding this opening.

10 The opening is closed by a hinged door 30 of dished construction to complete the semi-spherical shape of the interior of the clothes basket 20. The edge of the door 30 is preferably sealed against the door frame 28 by means of a rubber gasket 32.

The flange 24 also serves to clamp to the base casting 18, the periphery of a flexible rubber diaphragm 34, which, under the influence of fluid pressure admitted between the diaphragm and 20 the base casting 18 of the basket 20, acts to squeeze the clothes, or other materials being washed, against the perforated casing and thereby extract the cleaning fluid therefrom. The space between the perforated casing 22 and the 25 imperforate outer casing 26 provides means for draining away the fluid thus extracted.

Surrounding the shaft 12 is a hollow shaft or sleeve 34 having secured to its lower end a worm wheel 36 adapted to be driven by a worm gear 38 secured to the armature shaft 40 of an electric motor 42, and having at its upper end adjacent the base casting 18 of the clothes container 20, an inclined plate or flange 44.

35 Annular thrust bearings 46 and 48 are preferably interposed between the flange 44 and the bottom of the base casting 18 and between the lower face of the worm wheel 36 and the upper face of the boss 11 respectively.

The base casting 18 of the clothes container 40 preferably has a depending annular flange 50 surrounding the bearing 46 and adapted to accommodate a grease and water seal 52 between itself and the edge of the inclined plate 44.

It will be easily understood that upon the operation of the motor 42 the container 20 is progressively wobbled by the rotation of the inclined plate 44 but is held against rotation by the shaft 12 and the universal joint 16.

I prefer to dispose a drain pan underneath the container 20 and in the illustrated embodiment this drain pan may form a cover 54 for the box-like base 10 of the machine. The pan is preferably sloped to a convenient point where an opening 56 is provided leading to a suitable drain hose 58. The drain pan 54 is formed with a boss 58

which forms a bearing for the hollow shaft 34 and which extends high enough to act as a seal against the leakage of water down past the shaft.

The machine may be provided with a cabinet 60 enclosing the container and having a hinged door 62 arranged at an incline for easy access to the container and positioned so as to be coincident with the door 30 of the container when the container is in a predetermined position.

To insure that the container always stops at this position, I provide a detent 64 slideable in a framework 66 secured to the boss 11 and urged by a spring 68 into a groove 70 formed on the lower face of the worm wheel 36. A solenoid 72 is arranged to act on the detent 64 to withdraw it from the slot, while the motor is operating, and release it when the motor is stopped. Since the momentum of the apparatus is sufficient to carry the shaft 34 around at least one revolution, the detent will always catch in the groove 70 and halt the container at the proper place.

Hot and cold water are connected to the machine by two pipes 74 and 76 respectively which lead to two valves 78 and 80 respectively having a common outlet conduit 82 on which is positioned a thermostatic switch 84 for a purpose to be explained below. A branch 86 of the cold water conduit 76 leads to a third valve 88 which discharges into a conduit 90. The three valves are arranged to be opened by three solenoids 92, 94, and 96 attached to the valves 78, 80 and 88 respectively.

The conduits 82 and 90 lead to separate chambers 98 and 100 of a dual positive displacement pump 102. This pump may be of any desired type and is here shown as a sliding vane eccentric rotor pump. The pump is driven by the motor 42 and its shaft may be an integral extension of the armature shaft 40 of the motor.

The chamber 98 of the pump 102 discharges into a conduit 104, which extends into the clothes container 20 and is formed with a nozzle 106 discharging downwardly into the chamber 20 from a point near the door frame 28.

The chamber 100 of the pump 102 discharges into a conduit 108 which carries the water discharged from this chamber into the space between the diaphragm 34 and the base casting 18 of the clothes container.

Both of the conduits 104 and 108 are formed with flexible portions adapted to permit the motions of the clothes container to take place.

A fluid pressure operated switch 110 is mounted on the conduit 108 and is constructed and arranged to open an electric circuit when the pressure in that conduit reaches a value sufficient to carry out the extracting operation on the clothes, but insufficient to stall the motor.

Positioned at the lowermost portion of the clothes container 20 when it is in the position determined by the operation of the detent 64 is a double acting drain valve 112 having a passage 114 leading from the space between the casings 22 and 26 of the clothes container, and a passage 116 leading from the space between the diaphragm 34 and the container base 18. The valve includes a valve member 118 urged by a spring 120 to a position in which the passage 116 is open and the passage 114 is closed, and actuated by a solenoid 122 to a position in which the passage 114 is open and the passage 116 is closed.

The operation of the various solenoids and the turning on and off of the motor 42 is controlled in a predetermined cycle (such as that illustrated in Figure 6) by an automatic multiple cyclic

switch 124 which may be of the type disclosed and claimed in an application of Rex Earl Bassett, Jr., Serial No. 137,661, filed April 19, 1937.

This switch comprises a switch driving motor 126 of a constant speed type such as a synchronous motor, driving a shaft 128 through suitable reduction gears 130 and a ratchet clutch 132.

The shaft 128 is provided with an indicator 134 which runs over a dial (not shown) suitably positioned on the machine and serving to indicate the period of the cycle in which the machine is operating. This indicator 134 may be formed as a handle or knob which may be grasped by the operator to advance the shaft 128 to start the machine or to shorten one of the periods of the cycle.

On the shaft 128 are six cams 136 adapted to move six switch contacts 138 into and out of engagement with a contact bar 140. The contact bar 140 is connected to one line 142 of a 110 volt alternating current supply, and the contacts 138 are connected to six parallel circuits leading to the other line 144 of the current supply. A circuit 146 passes through the switch motor 126. A circuit 148 includes the driving motor 42 and the detent solenoid 72 arranged in parallel. A circuit 150 passes through the hot water valve solenoid 92. A circuit 152 passes through the cold water valve solenoid 94 and the thermostatic switch 84 arranged in series. A circuit 154 passes through the solenoid 96 and the pressure switch 110 in series. A circuit 156 passes through the drain valve solenoid 122.

A manually operable selector switch 158 is arranged to connect the two circuits 150 and 152 in parallel so that the solenoids are operated simultaneously by the hot water cam. It will be observed that, if both the hot and cold washing water solenoids 92 and 94 are energized by their respective cams, hot and cold water will be admitted simultaneously to the washing container. However, the cold water solenoid 94 is controlled by the thermostatic switch 84 to give a predetermined temperature of mixed water. As it is desirable, when washing cottons and similar goods, to use the hottest water available, the cold water solenoid 94 is not energized by its respective cam during the washing period but only during the rinsing period. However, if warm water is desired when washing woolens, the selector switch is closed so that the cold washing water solenoid 94 is energized for the wash period as well as for the rinse periods.

In operation, referring to the diagram of Figure 7, the automatic switch 124 is initially in the "off" position and consequently none of the contacts 138 are closed and all parts of the machine are at rest. The operator opens the doors 30 and 62 and places a quantity of clothes or other materials to be washed into the container 20 together with soap or other detergents. The doors are then tightly closed, and, after the operator has selected the water temperature suitable for the type of material by means of the selector switch 158, she advances the automatic switch indicator 134 to the point marked start (Fig. 7). This energizes the solenoid 72 to withdraw the detent 64 from the groove 70, starts the motor 42, and energizes the appropriate washing water solenoids to admit water to the pump chamber 98 from whence the pump discharges it into the washing container 20 through the nozzle 106. By forming the cams to maintain the water valves open a predetermined time, a pump of the type here

used will discharge a suitable fixed quantity of water into the tub, thus eliminating the necessity for a float valve or other water level determining device.

After the indicator 134 has passed the "fill" period, the operator may advance the indicator to reduce the washing time as desired, depending on the character and quantity of the soil in the clothes.

At the end of the washing period the motor 42 stops and the drain valve solenoid 122 is energized to open the passage 114 and permit the washing water to empty from the container. The detent 64 is released and holds the container with the drain valve in its lowermost position as shown in Figure 1.

The next operation is a rinse in which the motor 42 is started and container 20 is first filled with a quantity of clean water and then run for an additional period to thoroughly agitate the clothes in the water.

The next operation is a drain and flush in which the motor 42 continues to operate while clean water is sprayed onto the clothes from the nozzle 106 to help remove curds of soap and the like. The drain valve passage 114 is held open and is intended to be large enough to discharge more water than is sprayed in so that the level in the container is materially reduced and the spray has an opportunity to strike the clothes and thoroughly flush them.

The motor 42 is then stopped and the drain valve passage 114 remains open to fully complete drainage of the rinse water.

Next the motor 42 is started and run for a few minutes without water in the container. This tends to spread the clothes out more or less evenly over the bottom of the container 20 and is called the "distribution" period on the chart of Figure 7.

Now the solenoid 96 is energized to admit water through the conduit 90 to the pump chamber 100, and from there through the conduit 108 to the space between the diaphragm 34 and the base casting 18 of the container 20.

The water inflates the diaphragm and causes it to squeeze the clothes against the perforated inner casing 22 of the container 20.

The pump 102 is capable of producing a pressure greatly in excess of normal city water pressure and consequently enables the diaphragm to exert great pressure and dry the clothes to a much greater degree than can be done with an ordinary roll type wringer.

When the diaphragm is so fully inflated that all the space of the container 20 is occupied the pump can discharge very little more water and consequently the pressure rises rapidly and would stall the motor 42. Consequently when an adequate pressure is obtained below this stalling pressure, the pressure switch 110 opens the circuit 154, thus de-energizing the solenoid 96 and closing the valve 88 to cut off further admission of water to the pump chamber 100.

After a suitable period under pressure, the motor 42 stops, the drain valve slide 118 shifts

and the water is permitted to drain from beneath the diaphragm, after which the switch motor 126 stops.

The operator may then open the doors 38 and 62 and remove the clothes which are now substantially ready for ironing.

While only one embodiment of my invention has been shown in detail, it is not my intention that the scope of my invention be limited to that embodiment or otherwise than by the terms of the appended claims.

I claim:

1. A cleaning machine comprising a container, a support therefor, driving means for imparting a progressively wobbling non-rotating motion to the container, a diaphragm in the container and fluid pressure means for actuating the diaphragm to compress the contents of the container, said container having a drain at one side and its support being provided with means for holding said container stationary with the drain side tilted downwardly and with said diaphragm under pressure.

2. A cleaning machine comprising a rotatable hollow shaft having an inclined plate at its end, a stationary shaft within the hollow shaft, a container having its base engaged and progressively wobbled by said plate and universally centrally jointed to the stationary shaft and held from rotation thereby, a diaphragm in the container peripherally secured to the base of the container, a drain at one side of the container in the bottom thereof, two inlets for liquid under pressure at the opposite side of the container opening to the space on opposite surfaces of the diaphragm, and means for insuring that said container when it stops will have said drain at its lowermost point.

3. A cleaning machine comprising a container, a diaphragm therein, driving means for imparting progressively wobbling non-rotating motion to said container, a drain at one side of the container in the bottom thereof, two inlets for liquid under pressure at the opposite side of the container opening to opposite surfaces of the diaphragm, and means for insuring that said container when it stops will have said drain at its lowermost point.

4. A cleaning machine comprising a container, a diaphragm therein, driving means for imparting a progressively wobbling non-rotating motion to said container, said container being provided with fluid pressure means for actuating the diaphragm to compress the contents of the container, said container having a drain at one side, a support for said container provided with means for holding said container stationary with the drain side tilted downwardly and with said diaphragm under pressure, together with a cabinet housing said container, said container and said cabinet having openings which are in alignment when said container is held stationary but out of alignment when said container is wobbled to any of its other positions.

OLIVER J. CHAYIE.
